UNITED STATES PATENT OFFICE.

J. H. SMITH AND G. W. SMITH, OF PORT CHESTER, NEW YORK, ASSIGNEES
TO J. H. SMITH AFORESAID.

IMPROVEMENT IN TOMBSTONES.

Specification forming part of Letters Patent No. 35,978, dated July 22, 1862.

To all whom it may concern:

Be it known that we, J. H. SMITH and G. W. SMITH, both of Port Chester, in the county of Westchester and State of New York, have invented a new and useful Improvement in Tombstones; and we do hereby declare that the following is a full, clear, and exact description of the same, reference being had to the accompanying drawings, forming a part of this specification, in which—

Figure 1 represents a longitudinal vertical section of our invention. Fig. 2 is a transverse vertical section of the same.

Similar letters of reference in both views indicate corresponding parts.

The object of this invention is to facilitate the operation of connecting the tablet or head-stone with the base or pedestal and to conceal all traces of this operation or of the cement used in the same.

The invention consists in the arrangement of channels leading from below through the bottom of the pedestal to the socket which receives the tablet in such a manner that the sulphur or other material used for fastening the tablet in the pedestal can be poured in from below, and that when the stone is in an erect position no traces of the cement or of the cementing operation are visible.

To enable those skilled in the art to make and use our invention, we will proceed to describe it with reference to the drawings.

The base or pedestal A of our tombstone is formed in the ordinary manner, and it is provided with a socket, a, to receive the lower end, b, of the tablet or head-stone B. That part of the tablet or head-stone which enters the socket is made smaller than the rest, leaving a shoulder, c, which projects over and conceals the edges of the socket.

The usual cement used for securing the tablets in the pedestals is sulphur, and the ordinary manner of introducing this cement is through channels passing down from the top

of the pedestal, and by these means the surface of the pedestal is marked or deformed; and, furthermore, it is very difficult to remove from the surface of said pedestal the traces of the cement, whereby its appearance is still further spoiled. These disadvantages we have obviated by means of channels d, leading from the bottom of the pedestal to the socket a, as clearly shown in the drawings. Through these channels we introduce the sulphur or other cement, and in order to permit said cement to spread readily through the socket we provide the lower part, b, of the tablet with grooves or notches e; or said part may be fluted in a transverse direction or simply made rough, leaving sufficient room between its outer surface and the sides of the socket for the cement. After the tablet and the pedestal have been prepared in this manner the tablet is turned upside down and the pedestal put on, and the sulphur or other cement can now be conveniently poured into the channels d, and as soon as the cement is hard the stone is brought in an upright position, and all traces of the channels or of the cement are rendered perfectly invisible.

It is obvious that this invention is applicable to all tombstones composed of a pedestal and tablet, or of two or more parts of a similar description.

Having thus fully described our invention, what we claim as new, and desire to secure by Letters Patent, is—

Introducing the sulphur or other cement generally used for securing together the tablets and pedestals of tombstones through channels d, passing up from the bottom of the pedestal, substantially in the manner and for the purpose herein shown and described.

J. H. SMITH.
G. W. SMITH.
